(57) **CLAIM**

The ornamental design for a digital camera, as shown and described.

DESCRIPTION

FIG. 1 is a front, top, and right side perspective view of a digital camera showing our new design;

FIG. 2 is a front view thereof;

FIG. 3 is a top plan view thereof;

FIG. 4 is a right side view thereof;

FIG. 5 is a left side view thereof;

FIG. 6 is an enlarged portion view taken along lines 6-6 and 6-6 in FIG. 1;

FIG. 7 is an enlarged portion view of a taken along lines 7-7 and 7-7 in FIG. 2; and,

FIG. 8 is an enlarged portion view of a taken along lines 8-8 and 8-8 in FIG. 3.

The dashed-dot-dot-dashed lines form the boundary of the enlarged portion view of FIGS. 6-8 and form no part of the claimed design. The dashed-dot lines also show boundary of the claim and form no part of the claimed design. The even dashed broken lines shown in the drawings are included for the purpose of illustrating portion of the digital camera that form no part of the claimed design.

1 Claim, 7 Drawing Sheets
